UNITED STATES PATENT OFFICE

JOHN HUTTER, OF LOS ANGELES, CALIFORNIA, ASSIGNOR TO A. J. BAYER COMPANY, OF LOS ANGELES, CALIFORNIA, A CORPORATION OF CALIFORNIA

DESIGN FOR A GRAVE MARKER

Application filed April 18, 1931. Serial No. 39,541. Term of patent 7 years.

To all whom it may concern:

Be it known that I, JOHN HUTTER, a citizen of the United States, residing at Los Angeles, in the county of Los Angeles and State of California, have invented a new, original, and ornamental Design for Grave Marker, of which the following is a specification, reference being had to the accompanying drawings, forming part hereof.

Figure 1 represents a plan view of a grave marker embodying my design; and

Figure 2 represents a side view thereof.

The essential features of the design are the panel having the leafy sprays thereon framing the name, relationship and data concerning the life span of the deceased.

I claim:

The ornamental design for a grave marker, substantially as shown, and described.

JOHN HUTTER.
